United States Patent Office.

RICHARD C. LAMBART, OF RAYNHAM, ASSIGNOR TO DAVID WHITTEMORE,
OF NORTH BRIDGEWATER, MASSACHUSETTS.

Letters Patent No. 96,817, dated November 16, 1869.

IMPROVEMENT IN HEEL-CUTTING MACHINES.

The Schedule referred to in these Letters Patent and making part of the same.

To all whom it may concern:

Be it known that I, RICHARD C. LAMBART, of Raynham, in the State of Massachusetts, have invented certain new and useful Improvements in Heel-Cutting Machines; and I do hereby declare the following to be a full and correct description of the same, reference being had to the accompanying drawings, in which—

Figure 1 represents a plan view of improvements for jacking the shoe, and cam for operating the knife, and a corresponding sectional view of the rocking-knife and its stock.

Figure 2 represents a plan view of the latter, and a sectional view of the cam and jack improvements.

These improvements have particular reference to a heel-cutting machine invented by me, and patented to David Whittemore, in Letters Patent, No. 76,207, dated March 31, 1868.

They consist—

First, in the means for securing the shoe to the jack.

Secondly, in giving to the knife-stock an adjustment for changing the bevel of the heel.

Thirdly, in so hanging the knife as to allow its edge a rocking motion to and from the heel, and in attaching to the jack a cam, which, as the jack turns, operates upon the knife, and causes the latter, at all times, to be presented flatwise to the heel, and at such an angle as will best facilitate the proper cutting.

Fourthly, in various details of construction, herein after more particularly set forth.

In the improved machine, the heel-pattern, marked A in the drawings, is attached to the jack in the same manner as in the patented machine above referred to. The toe-clamp, however, is omitted, and the shoe is secured to the pattern by a new device, which I proceed to describe.

The pattern is made with a detachable heel-plate, B, of the shape of the pattern, and having two pins, a a, as shown.

This plate has a lever or handle, c, as shown.

The part of the lever underneath the plate fits into a groove extending lengthwise along the top of the pattern, thus fastening the plate to the pattern.

The plate is more firmly secured by the dowel-pin d, shown in the groove of the pattern, and by another pin, e, extending from the lever down in front of the pattern.

Each pattern is furnished with several heel-plates.

The shoe is put upon a plate outside of the machine, the heel being held by the two pins a and a. The plate, with the shoe thus attached, is then secured to the pattern, and the shoe chucked, as in the old machine.

The jack and pattern turn and slide as before.

The pattern has rigidly attached to it a cam, D, as shown, which operates upon a pin and roller, R, connected with the knife, as will be presently described. The cam is concentric with the pattern along the straighter parts of the heel, but swells beyond the latter at the top curve.

The knife-stock X is connected with the hand-lever, substantially as in the old machine, but to give another adjustment to the knife, for changing the bevel of the heel, the stock is attached to the intermediate slide by pins passing through the holes s and t. The pin passing through the hole s is the pivot. The other pin is furnished with a screw and nut, by means of which the stock is rigidly secured to the slide.

To allow the edge of the knife a movement to and from the heel, the knife-stock is divided into two parts, as shown, the knife Y being attached to a rocking frame, X', within the stock, as shown. The guides x and y, one running in the rand of the shoe, and the other in contact with the edge of the pattern, belong to the rocking frame X', as shown. The rocking frame is attached to the arms m m of the stock, by two pivots l l, as shown.

The rocking knife-frame is furnished with a roller, R, against which the cam D works as the jack turns or slides. The roller is mounted upon a pin projecting from the frame, nearly on a line with the knife.

One arm, m, of the stock X, extends down in front of the roller, as seen in fig. 2, and serves as a stop to prevent the knife from cutting too deep into the heel.

In order that the roller R may be kept in contact with the cam while the machine is in operation, the cam is made with a guide, s s, the cam and guide forming a cam-groove equal in breadth to the diameter of the roller, with the exception of the recesses v and v'.

The roller slips into one of these recesses, when the spring connected with the hand-lever, as shown in the old machine, operates upon the slide to lift the knife from contact with the heel.

The operation of the improved machine is as follows:

The shoe is jacked, as hereinbefore described, and the jack is operated as in the old machine. Before the jack moves, the roller R is in the recess v. When the hand-lever of the old machine is pressed down, to bring the knife into contact with the heel, and the jack is started, the roller leaves the recess, and is brought into contact with the cam. At the same time, the whole of the end of the guide y is brought into contact with the pattern, which keeps the knife in a proper position to successfully operate, the jack turning so that less and less of the guide y remains in contact with the pattern. The cam, swelling beyond

the pattern, acts upon the roller to keep the knife constantly at the required angle. The rest of the operation is obvious.

The improved parts are all of metal, and the weight of the frame X tends to steady the knife.

I claim—

1. Constructing the pattern with a detachable heel-plate, substantially as described, for the purposes specified.

2. The knife R, hung so as to allow its edge a rocking motion to and from the heel, in the manner described.

3. The combination of the cam D, with the rocking-knife B, for the purpose set forth, in the manner specified.

4. The combination of the pattern, the guide y, the cam, and the rocking knife, substantially as described.

5. Securing the knife-stock to the machine by means of the hole s and slot t, to allow an adjustment for changing the bevel of the heel.

The above specification of my said invention signed and witnessed at Boston, this 13th day of August, A. D. 1869.

RICHARD C. LAMBART.
